UNITED STATES PATENT OFFICE.

CHARLES EDWARD CHITTENDEN, OF AUCKLAND, NEW ZEALAND.

FLUSHING DEVICE.

Application filed May 21, 1924. Serial No. 714,968.

To all whom it may concern:

Be it known that I, CHARLES EDWARD CHITTENDEN, a subject of the King of Great Britain and Ireland, residing in Auckland, 5 in the Dominion of New Zealand, have invented a new and useful Improvement in Flushing Devices; and I do hereby declare the following to be a full, clear, and exact description of the same.

10 This invention relates to flushing devices used for flushing water closets and the like, and particularly to that class of device in which a float is employed to operate mechanism to close a valve in order to cut off the 15 water supply.

The object of the present invention is to provide an improved flushing device which will operate silently and at the same time give a good flush.

20 According to my invention, the device consists of a chamber divided into a valve compartment and a float compartment connected by a by-pass opening at the bottom thereof below the valve in the valve compartment, while an outlet pipe of smaller diameter than the opening controlled by the valve leads from the valve compartment. A lever in the valve compartment is controlled by an operating handle and flexibly connected to the valve, a pivoted catch above said valve having a hooked end formed with a sloping face to engage a sloping end upon the end of the lever, such catch engaging the lever by gravity when the lever is raised and 30 disengaging the lever as the float rises.

Approved forms of the invention are shown in the accompanying drawings, wherein:—

Figure 1, is a sectional elevation through 40 the device.

Figure 2, is a sectional plan on line A—A.

Figure 3, is an enlarged view of the valve control mechanism.

Figure 4, shows the apparatus set up in 45 position.

Figure 5, is an elevation of a modified form of valve control mechanism.

Figure 6, is a side view thereof.

50 Referring to the drawings, the device consists of a chamber 1 formed into compartments 2 and 3. From the compartment 2 a down-pipe 13 leads to the pan 12 to be flushed while a water inlet pipe 4 enters the top of the compartment 2 and can be always 55 open thereto. In the compartment 2 is a

valve seat 5 controlled by a valve 6. This valve is connected by a chain 7 or other flexible connection to a lever 8 fixed upon a spindle 9 entered in bearings 26 in the walls of the chamber. One end of the spindle 9 passes through a wall of the chamber and is provided with a handle 11. Suitable stuffing boxes are provided where the spindle passes through the chamber in order to prevent leakage. A catch 14 fixed upon a pin 15 pivoted in the wall of the chamber has a hook like end provided with a sloping face 16 adapted to engage a similarly sloping face upon the end of the arm 8, the slope being such that when in engagement, as shown in Figures 1 and 3, the catch 14 will support the lever 8 and the valve 6, but when the catch is lifted to the position shown in dotted lines in Figure 3, the hooked end will move clear of the end of the lever 8. The catch is connected at its forward end by means of a chain 17 or other flexible connection to an arm 18 fixed to a spindle 19 which is mounted in a bearing 20 in the dividing wall between the two compartments, such bearing also forming a stuffing box. The spindle 19 projects into the compartment 3 which forms a float tank. On this end of this spindle another arm 21 is fixed and has pivoted at its end a rod 22 projecting from a float 23. A by-pass 24 for water opens at the bottom of the compartment 2 into the float tank 3.

90 In operation, the valve 6 is raised to allow water to pass through the valve seat into the flushing pipe 13 by the operator turning the handle 11 on the spindle 9. This operation raises the lever 8 which will move in an arc (indicated by the dotted lines in Figure 3) and will raise the catch 14 until the hooked portion reaches the position shown in dotted lines in Figure 3, when it will immediately fall by gravity and will be engaged by the sloping face upon the end 95 of the lever 8 as such lever returns downwardly, thus retaining the valve 6 in an open position. As the water passes through the valve a certain quantity is diverted by the by-pass 24 into the float tank, the opening 100 into the down pipe being for this purpose less in area than the area of the opening through the valve seat, and raises the float and this water causes the arm 21 to rotate the spindle 19 thereby raising the arm 18 105 and lifting the catch 14 which, as soon as 110

it is raised sufficiently (see dotted lines in Figure 3) will become released from the sloping end of the lever 8 permitting the valve to return to its seat and shut off any further supply of water. Water in the part 3 then flows through the by-pass 24 and permits the float to drop into its normal position.

A suitable vent hole 25 is provided in the top of the float tank.

10. As shown in the modified form in Figs. 5 and 6, in place of the chain 17 a cam 25^a is mounted on a rod 26^a journalled in the walls of the chamber 1 and adapted to be raised by the float 23, and for this purpose the arm 18 is pivotally connected by a link 27 to the cam 25^a. As the float rises the arm 18 will raise the cam which in turn will raise the catch 14 and so release the arm 8 to allow the valve 6 to fall.
20. Suitable means may be provided to enable the operating handle to become free of the spindle after the lever 8 has been raised sufficiently to engage the catch 14 so that the valve cannot be held open longer than 25 is necessary for the required amount of flushing water to pass through.

While I have described in the foregoing specification the construction of parts and operation preferred, I do not limit myself 30 to the positive terms employed except such as the state of the art may require.

What I claim is:—

1. A flushing apparatus, comprising, a valve compartment, a valve in the valve compartment, a float compartment, a float in the float compartment, an outflow pipe connected to the valve compartment below the valve, a by-pass interconnecting the compartments, an operating handle, a lever in the valve compartment controlled by the operating handle, a flexible connection between the valve and the lever, a pivoted catch positioned above the lever, a sloping faced hooked end on the catch, an end face on the lever cooperating with the sloping portion of the catch to engage the lever with the catch by gravity when the lever is sufficiently raised, and connecting means between the catch and the float whereby rising of the float causes disengagement of the catch 50 from the lever.

2. A flushing apparatus according to claim 1, said connecting means including, a spindle passing from the float compartment to the valve compartment, an arm on the spindle, a connection between the arm and the float, a second arm on the spindle and a flexible connection between the second arm and the catch.

In testimony whereof, I have signed my name to this specification.

CHARLES EDWARD CHITTENDEN.
